UNITED STATES PATENT OFFICE.

GUSTAV F. W. SCHULTZE, OF OAKLAND, CALIFORNIA.

COIN-CONTROLLED WEIGHING-SCALE.

1,134,559.

Specification of Letters Patent.

Patented Apr. 6, 1915.

Application filed November 26, 1913. Serial No. 803,284.

To all whom it may concern:

Be it known that I, GUSTAV F. W. SCHULTZE, a citizen of the United States, residing at Oakland, in the county of Alameda and State of California, have invented certain new and useful Improvements in Coin-Controlled Weighing-Scales, of which the following is a specification.

The hereinafter described invention relates to means for regulating the return of a deposited coin or token to the depositer thereof within a coin actuated device, or the retention thereof within the machine as a compensation for the value given therefor, the construction and operation of the working parts being such that the user of the machine is given an opportunity to have returned the deposited coin or token, depending on the registering of a guess as to which slot in the interior of the casing the coin for throwing into operation the actuating mechanism will be directed; the object of the invention being to create an interest and attract attention to the coin controlled machine and by so doing causing a greater number of persons to use the machine than otherwise would be the case.

The invention is adapted for use in connection with any form of a coin controlled vending machine, but for the purpose of illustration, the same is disclosed as applied to an ordinary coin actuated weighing machine, wherein a charge is usually made for giving the weight of the user thereof. Usually, the user of such devices deposits a coin or token and in return is given his weight, the coin being retained within the machine as payment therefor, or in case of a coin controlled vending apparatus a given quantity of merchandise is discharged from the machine in consideration of the deposited coin or token.

In the present case the user of the machine is given a choice of guessing into which interior coin runway the actuating coin will be directed. Should the guess of the interior coin runway be the one set to return the coin, the deposited coin or token is directed to the exterior of the machine for the recovery thereof, and in such an event, the user is given that which is controlled by the apparatus and in addition has returned the

coin or token deposited for actuating the machine.

In the case of a weighing scale, the weight of the user is given and the deposited coin returned, and in the case of a vending machine, the merchandise controlled thereby is discharged and the coin or token returned. In either event, the return of the coin or token to the user of the machine, or the retention thereof within the machine, is dependent solely on the registering of a guess by the user as to the interior coin runway into which the actuating coin or token will be directed when deposited into the machine.

If a guess be not registered as to which interior runway the coin will be directed on being deposited into the machine, the coin will be retained by the machine.

After each guess and operation of the scale, the guessing mechanism is restored to its normal position for directing all coins or tokens into the casing until such time as another guess may be registered.

With the above mentioned and other objects in view, the invention consists in the novel construction and combination of parts, hereinafter described, illustrated in the accompanying drawing, and pointed out in the claims hereto appended; it being understood that various changes in the form, proportion, size and minor details of construction may be resorted to without departing from the spirit or sacrificing any of the advantages of the invention.

To comprehend the invention reference should be had to the accompanying drawings, wherein is disclosed one form of my invention, and in which the same is illustrated as applied to a weighing apparatus.

Figure 1 is a side elevation of a spring scale, with the upper portion in vertical section, disclosing the scale mechanism and the mechanism for registering a guess as to the disposal of the actuating coin. Fig. 2 is a vertical sectional view of the scale casing viewed from the rear, disclosing the weighing mechanism, the mechanism for directing the coin into certain runways, and the mechanism for registering a guess as to the disposal of the actuating coin. Fig. 3 is a sectional view taken on line 3-3 of Fig. 2. Fig. 4 is a rear view of the mechanism for

guessing the disposal of the coin dependent upon the interior runway into which the same has been directed. Fig. 5 is a sectional view taken on line 5—5 of Fig. 2. Fig. 6 is 5 a sectional view taken on line 6—6 of Fig. 2. Fig. 7 is a view of the guess registering dial and hand and the cup for receiving the discharged coin.

Referring more particularly to the drawings, the reference numeral 1 designates a suitable scale base on the forward portion of which is mounted the scale platform 2, and from the rear of the base extends the vertical casing 3, in which is mounted the operating 15 mechanism of the scale.

The weight indicating mechanism of the scale is constructed in the following manner:—Extending vertically within the casing 3 is a scale rod 4, connected at its lower end to the platform mechanism and carrying at its upper end a transverse bar 5, connected at each end to suitable coiled springs 6, suspended at their opposite ends from a suitable bar 7, supported by the interior side 25 walls of the casing 3. Slidably mounted in a suitable guide 8 formed on a plate 9, attached to the interior of the front wall of the casing 3 in rear of a dial opening 10, adapted to be inclosed by a glass 11, is a bar 12, the lower end of which rests on the transverse bar 5 and the upper end of which is provided on one face with teeth 13, which intermesh with a pinion 14 loosely mounted on a horizontal shaft 15, one end of which 30 is journaled in the upper portion of the plate 9, and the other end is journaled in and extends through a dial plate 16 positioned in rear of the dial opening 10, and secured to the outer end of said shaft 15 between the 35 glass 11 and the dial plate 16, is an indicating hand 17, adapted to rotate about the face of the plate 16 and indicate the weight of the user of the scale. The pinion 14 is provided on one surface with an arm 18 40 adapted to contact with a corresponding pin 18' projecting from one surface of a disk 19, secured to the shaft 15, and mounted on the shaft adjacent the disk 19 is a grooved pulley 19' to which is fastened one end of a 45 flexible cord 20, the opposite end of which supports a suitable weight 21.

Secured at its lower end to the transverse bar 5 is a suitable rod 22 which is of sufficient length that the upper end thereof is 55 adapted to engage a plate 23, pivoted at one end to a bracket 24 and provided at its opposite end with a suitable pointed tongue 25 which is normally unseated from suitable teeth formed in the peripheral edge of 60 the disk 19, the end of the rod 22 when in engagement with the plate 23 lifts the tongue 25 thereof, from the teeth in the edge of the disk 19, but should a person step on the scale platform, the rod 22 will be pulled

downwardly with the bar 4 and the tongue 65 25 will fall into engagement with the ratchets and prevent the lower end of the bar 12 from following the scale rod downwardly, until such time as a coin is inserted in the machine. 70

The coin operated releasing mechanism is preferably constructed in the following manner:—Formed in the front wall of the casing 3, preferably at the right side of the dial 10, is a coin receiving opening 26, at 75 the inner end of which is positioned a coin receiving cup 27 open at its outer side, as at 28, and said cup is secured to the end of a suitable arm 29 pivoted, as at 30, adjacent the plate 23, and said rod is formed with a 80 finger 31 adapted to extend under the plate 23. A weighted arm 32 extending over the plate 23 is also provided on the rod 29 and said arms are of sufficient weight to maintain the cup 27 carried at the opposite end 85 of the rod in position to receive a coin from the slot 26.

Positioned to receive the coin from the cup 27 is an open mouthed flared tube 33 divided within its length into a plurality of 90 oblong coin receiving slots 34 and 35 which are arranged at their lower ends in substantially longitudinal alinement with each other, and each slot is open at its lower end, as at 36, and at their outer lower side edges, 95 as at 37. Pivotedly mounted in the tube 33 above the division wall therein, is a shaft 38, carrying a plate 39 which directs the deposited coin or token into either the slot 34 or the slot 35. One portion of said shaft is 100 formed with a laterally extended weighted arm 40 and the end of said shaft is curved as at 41 and engages the peripheral edge of the disk 42, provided with serrations 42' of different depths, and said disk is mounted on a shaft 43 journaled in plates 44 carried by the frame 9, and said disk carries a pivoted spring pressed pawl 45 which engages the ratchets 46 of a disk 47 carried by a drum 48 which is loosely mounted on the 110 shaft 43. A flexible cord 49 surrounds the drum 48 and is connected at its opposite ends to the points 50 and 51 of an arm 52 formed on the bracket 53 which is secured to the scale rod 4. 115

It will be apparent that each time a person stands on the scale platform 2, the rod 4 will be drawn downwardly carrying the arm 52 and bracket 53 with it, and this will cause the lower end of the flexible connection to unwind from the drum and the upper end to wind thereon, and the rotation of the drum, will, through the pawl 45 and ratchets 46, cause the disk 42 to rotate, and the curved end of the shaft 41 dropping into 120 the serrations 42' will cause the directing plate 39 to oscillate. When the disk comes to a stop and the curved end 41 of the shaft 125

is resting in one of the deep serrations, the directing plate will be in a position to direct the coin into the slot 34, but if the curved end should rest on one of the serrations 5 that is not so deep, then the plate will be in a position to direct the coin into the slot 35.

The mechanism for registering a guess as to which slot the coin will be directed into 10 and controlling the return of the coin to the user, or the retention thereof within the machine, is constructed and operates in the following manner:—Loosely mounted on a rotatable shaft 54 and positioned below the 15 discharge ends of the slots 34 and 35, is a plate 55, provided with a flanged edge 56 formed with an opening 57 therein, which is of a width corresponding to the width of one of the slots, and said flange when positioned below the slots 34 and 35 closes the open ends of the same and directs the coin out of the side edges thereof, but, when the opening 57 in the flange is positioned under one or the other of said slots, it permits the 20 coin to pass from the lower end of said slot through a channel 58 leading to the exterior of the casing into a cup 59. An indicating hand 57' provided with a handle 57" is secured to the end of said shaft extending exteriorly of the casing and said hand operates over dial numbers 1 and 2, and when 25 said hand is in the normal full line position—Fig. 7, the flange of the plate is beneath the coin slots to direct the coin into 30 the interior of the casing.

The plate 55 carries on its rear surface a pin 60 and a segment 61 provided with teeth 62 and 63, and said teeth, when the plate is operated in the direction of the 40 arrow, are engaged by the end of a pawl 64 pivoted as at 65 and carrying at its rear end a spring 66 which forces the outer end of said pawl into engagement with said segment. A spring 67 normally retains the 45 plate in position, as in Fig. 4, with the side edge thereof resting on the pin 68. A controlling means in the form of a segmental frame 69 is keyed to rotate with the shaft 54 and is positioned immediately in rear 50 of the plate 55 and said frame when the shaft is rotated by the operator in the direction of the arrow—Fig. 4, engages the pin 60 and operates the plate 55 to present the opening 57 below the slot 34 or 35.

55 A cog wheel 70 of a clock work mechanism is secured to the shaft 54 and the same is engaged by a spring pressed pawl 71 carried by a cog 72 which is loosely mounted on the shaft and is connected thereto by a 60 spring 73, and said cog intermeshes with a cog 74 carried by a shaft 75 on which is mounted an escapement ratchet 76 controlled by the pivoted escapement pawl 77 from which depends the pendulum 78. The

pendulum is prevented from swinging when 65 a person is on the scale platform, and the rod 4 is depressed, by a finger 79 carried by a rotatable shaft 80 extending transversely of the casing, and said finger is normally forced upwardly until the stop 81 carried 70 by the shaft, engages a pin 82, by a weighted arm 83, which is raised on the upward movement of the bar 4 by a bracket 84 carried thereby.

The operation of the scale mechanism 75 and the mechanism for directing the coin into one or the other of the coin slots being clear, the operation of the guess registering mechanism is all that need be explained.

The operator stepping on the scale platform grasps the handle 57", and guesses which slot will return the coin by moving the hand 57' to the numeral 1 or 2. The moving of the indicator hand rotates the shaft 54 carrying the frame 69, which in 85 turn, through the pin 60, rotates the plate 55 against the tension of the spring 67, and if the hand is set on the numeral 2, the opening 57 in the flange 56 is positioned beneath the opening 36 of the runway 34, thus 90 permitting the coin, should the same be directed through the runway 34, to pass through the channel 58 into the cup 59 at the exterior of the casing, the flange 56 being positioned below the opening 36 of the runway 35 to direct the coin, should the same pass through the channel 35, through 95 the opening 37 at the side thereof into the interior of the casing. Should the hand be set on the numeral 1, the opening 57 will be 100 below the runway 35 and a portion of the flange will close the lower end of the runway 34. The end of the pawl 64 dropping into the respective ratchets 62 and 63 retains the plate in a position to present the 105 opening 57 thereof either below the runway 35 or runway 34. The rotation of the shaft 54 will wind the spring 73 of the clock-work mechanism, but the escapement pendulum 78 thereof, will be prevented from 110 operating by the finger 79, as the same is in a substantially horizontal position when the scale platform is occupied, and the standard 4 is depressed. The operator after having deposited a coin in the receiving opening 115 and having received his weight, the coin having been returned or retained within the casing dependent on the guess registered, steps off of the scale platform, the standard 4 is pulled upwardly by the springs 6 causing the finger 79 to be moved out of contact with the pendulum 78, which permits the same to swing, which in turn allows the spring 73 to rotate the shaft 54 causing the frame 69 to move therewith, and the movement of the frame will cause the peripheral edge thereof to contact with the pin 85 carried by the pawl 64 and raise the same from 120 125

whichever ratchet 62 or 63 in which the same may be seated, and the raising of the pawl will permit the spring 67 to return the plate 55 to its normal position, as in Fig. 4, with the indicating hand 57' in the full line position, as in Fig. 7.

It will be apparent that the dial mechanism will not operate until a coin is deposited into the coin receiving opening, that 10 the directing plate 39 will be operated on the downward movement of the standard 4, and that the flange 56 is normally in a position to direct the coin from either of the runways into the interior of the casing 15 when the operator fails to register a guess as to the path of travel of the coin.

It will also be apparent that the plate 55 after having been set, will return to its normal position on the operator leaving the 20 scale platform.

Having thus described my invention what I claim and desire to protect by Letters Patent is:—

1. In a weighing machine of the class 25 described, the combination with a casing provided with a coin receiving opening and a coin discharge opening, coin operated weight indicating mechanism situated within the casing, a plurality of coin runways 30 within the casing and communicating with said coin receiving and discharge openings, means for directing the deposited coin into one of said runways, and means whereby a guess may be registered as to the runway 35 into which the coin will be directed, whereby the coin deposited within the machine is returned to the user thereof, provided the registered guess as to the runway into which the coin will be directed corresponds to the 40 runway into which it is directed.

2. In a weighing machine of the class described, the combination with a casing, coin operated weight indicating mechanism situated within the casing, coin runways within 45 the casing, means for directing the actuating coin relative to said runways, means whereby a guess may be registered as to the disposal of the coin by the directing means whereby the actuating coin is returned to 50 the user thereof provided the registered guess as to the runway within which the coin is to be directed corresponds to the disposal of the coin by the directing means.

3. In a weighing machine of the class 55 described, the combination with a casing, coin operated weight indicating mechanism situated within the casing, coin runways within the casing, means for directing the actuating coin relative to said runways, means 60 whereby a guess may be registered as to the disposal of the coin by the directing means whereby the actuating coin is returned to the user provided the registered guess corresponds to the disposal of the coin by the

directing means, and means for locking the guess registering means in its adjusted position until the weight indicating mechanism is relieved of the user's weight.

4. In a weighing machine of the class described, the combination with a casing, coin operated weight indicating mechanism situated within the casing, coin runways within the casing, means for directing the actuating coin relative to said runways, 75 means whereby a guess may be registered as to the disposal of the coin by the directing means whereby the coin is returned to the user provided the registered guess corresponds to the disposal of the coin by the directing means, means for locking the guess 80 registering means in its adjusted position on the machine being occupied by the user, and means for automatically restoring the guess registering means to its normal position on the machine being relieved of the 85 user's weight.

5. In a weighing machine of the class described, the combination with a casing, coin operated weight indicating mechanism situated within the casing, means associated 90 with said indicating mechanism for receiving the weight of the user, coin runways within the casing, means operated by the actuation of the weight receiving means for directing the coin relative to said runways, and means whereby a guess may be registered as to the disposal of the coin by the directing means, whereby the coin is returned to the user, provided the registered guess as to the runway within which the coin 100 is to be directed corresponds to the disposal of the coin by the directing means.

6. In a weighing machine of the class described, the combination with a casing, coin operated weight indicating mechanism situated within the casing, means associated with said indicating mechanism for receiving the weight of the user, coin runways within the casing, means operated by the actuation of the weight receiving means 110 for directing the coin relative to said runways, means whereby a guess may be registered as to the disposal of the coin by the directing means, whereby the coin is returned to the user, provided the registered 115 guess corresponds to the disposal of the coin by the directing means, and means for locking said guess registering means in its adjusted position while said weight receiving means is occupied.

7. In a weighing machine of the class described, the combination with a casing provided with a coin inlet and a coin outlet opening, coin operated weight indicating mechanism situated within the casing, coin runways within the casing and in co-operative relation with said coin inlet and outlet openings, means for directing the coin rela- 125

- tive to said runways, and guess registering means operated by the user for guessing the disposal of the actuating coin relative to said runways, said means when operated 5 opening the discharge end of a certain one of said runways relative to said coin outlet opening and for closing the discharge end of a certain other of said runways relative to said outlet opening.
- 10 8. In a weighing machine of the class described, the combination with a casing provided with a coin inlet and a coin outlet opening, coin operated weight indicating mechanism situated within the casing, 15 means associated with said weight indicating mechanism for receiving the weight of the user, coin runways within the casing and in coöperative relation with said coin inlet and outlet openings, means operated by 20 the actuation of said weight receiving means for directing a coin relative to said runways, means operated by the user for opening the discharge end of a certain one of said runways relative to said coin outlet opening 25 and closing the discharge end of a certain other one of said runways relative to said coin outlet opening, means for locking the controlling means for the discharge ends of said runways in its adjusted position, 30 controlling means for said locking means locked from movement on the weight receiving means being occupied and unlocked on the weight receiving means being relieved of the weight of the user, and means for re- 35 turning the controlling means for the discharge ends of said runways to its normal position on the unlocking of said controlling means.
9. In a weighing machine of the class de- 40 scribed, the combination with a casing provided with a coin inlet and a coin outlet opening, coin operated weight indicating mechanism situated within the casing, coin runways within the casing and in coöperative relation with said coin inlet and outlet openings, means operated on the actuation of the machine for directing the operating coin relative to said runways, and means normally positioned to direct the coin from 45 said runways into the interior of the casing and operated by the user for opening the discharge end of a certain one of said runways relative to said coin outlet opening and for closing the discharge end of the other of 50 said runways relative to said discharge opening.
10. In a weighing machine of the class described, the combination with a casing provided with a coin inlet and a coin outlet opening, coin operated weight indicating mechanism situated within the casing, coin runways within the casing and in coöperative relation with said coin inlet and outlet openings, means operated on the ac- 55
- tuation of the machine for directing the operating coin relative to said runways, means normally positioned to direct the coin from said runways into the interior of the casing and operated by the user for opening the discharge end of a certain one of said runways relative to said coin outlet opening and for closing the discharge end of the other of said runways relative to said discharge opening, means for locking said last mentioned means in its adjusted position on the machine being occupied, and means for unlocking the locking means and for permitting the means for controlling the discharge ends of said runways to return to its normal position on the machine being relieved of the user's weight. 65
11. In a weighing machine of the class described, the combination with a casing, coin operated weight indicating mechanism within the casing, coin runways within the casing, means for directing the actuating coin relative to said runways, means whereby a guess may be registered as to the disposal of the coin by the directing means whereby the actuating coin is returned to the user provided the registered guess as to the runway within which the coin is to be directed corresponds to the disposal of the coin by the directing means, said guess registering means normally positioned to direct the coin from said runways to the interior of the casing. 70
12. In a weighing machine of the class described, the combination with a casing, a coin operated weight indicating mechanism situated within the casing, coin runways within the casing, means for directing the actuating coin relative to said runways, means normally positioned to direct the actuating coin from said runways into the interior of the casing, said means being capable of operation by the user to register a guess as to the disposal of the coin by the directing means whereby the actuating coin is returned to the user provided the registered guess as to the runway into which the coin is to be directed corresponds to the disposal of the coin by the directing means. 75
13. In a weighing machine of the class described, the combination with a casing, provided with a coin inlet and a coin outlet opening, coin operated weight indicating mechanism situated within the casing, coin runways within the casing and in coöperative relation with said coin inlet and outlet openings, means for directing the operating coin relative to said runways, means normally positioned to direct the coin from said runways into the interior of the casing and operated by the user for opening the discharge end of a certain one of said runways relative to said coin outlet opening and for closing the discharge end of the other of 80
